BROAD BAND DIRECTIVE ANTENNA

Philip S. Carter, Rocky Point, N. Y., assignor to
 Radio Corporation of America, a corporation of
 Delaware

Application November 24, 1942, Serial No. 466,721

16 Claims. (Cl. 250—33)

The present invention relates to traveling wave antennas and, more particularly, to such antennas designed to cover a wide frequency band.

It has heretofore been customary, when desiring an antenna useable over a wide band of frequencies, to utilize resistance terminated rhombic antennas. In using these antennas a high price is paid in lost radiation efficiency, directivity and in higher construction cost for the operating convenience of an aperiodic antenna. The usual resistance terminated rhombic type of antenna wastes about half of the transmitter output in the terminating resistance at the optimum operating frequency while at lower frequencies a much greater proportion of the power is lost. Since so much of the transmitted power is wasted in the resistance, the resistance terminated rhombic antenna must be designed to have about twice as much directivity to give a desired power gain in the desired direction as would be the case of other antennas having a higher radiation efficiency. Therefore, in using this type of antenna we must either be satisfied with a weaker signal or the vertical and horizontal spread of angles covered by the beam must be reduced by increasing the antenna dimensions. Furthermore, the directivity of the rhombic antenna decreases more rapidly with the change in frequency than with that of a V antenna of equivalent dimensions.

An object, therefore, of the present invention is to provide an antenna system which is free of the foregoing objections.

Another object of the present invention is to provide a uni-directional traveling wave antenna of high efficiency over a broad band of frequencies.

Still another object of the present invention is the provision of antenna, as aforesaid, in which the losses caused by the terminating resistance are avoided.

A further object of the present invention is the provision of a traveling wave antenna which is operative without substantial frequency discrimination over a wide band of frequencies.

Still a further object of the present invention is the improvement of the directivity of traveling wave antennas.

A further object of the present invention is the provision of an unloaded V type traveling wave antenna which is not adversely affected by a change in frequency.

The foregoing objects, and others which may appear from the following detailed description, are attained in accordance with the principles of

the present invention by the provision of a traveling wave antenna, including one or more elongated conductors energized at one end and said conductors being characterized in that they are so arranged as to have uniform current distribution over the length thereof. This may be attained by forming the conductors in the form of cones energized at their apices or by terminating the conductors of the antenna in conductive conical surfaces of revolution. If the proportions of said conical elements are properly chosen reflection at the free ends of the conductors may be avoided without using terminating resistances. Thus all of the energy applied to the wires is radiated and used to cause a sharply directive beam and none is wasted.

The novel features which, it is believed, are characteristic of the present invention are pointed out with particularity in the appended claims. The invention will, however, be more completely understood by reference to the following detailed description which is accompanied by drawings in which Figure 1 illustrates one embodiment of the present invention, while Figure 2 illustrates a modification of a portion of the antenna of Figure 1 and Figure 3 illustrates a further modification of the invention, while Figure 4 is a curve illustrating the current distribution along the length of a conductor of a V antenna and Figure 5 is a curve illustrating the current distribution along a conductor of a V antenna terminated by cones in accordance with one aspect of the present invention and Figure 6 is a curve showing the relationship between wavelength and percentage reflection on an antenna constructed according to the present invention.

The embodiment of the present invention shown in Figure 1 includes a pair of radiating conductors 10 and 11 arranged at an angle to one another and energized at their more closely adjacent ends by a transmission line TL connected to a suitable source of high frequency energy. Each of the conductors 10 and 11 is composed of a plurality of wires arranged along the surface of an imaginary cone. The apices of the conical conductors are each connected to one of the conductors of transmission line TL while the base of the cone is formed by the wires being connected to spreader rings 22. Additional rings (not shown) may be spaced along the length of the conductor in order to maintain the conical relationship between the wires. While only a few wires are shown as composing each of the conductors 10 and 11, an actual physical em-

bodiment of the invention may actually employ sixteen or more wires. The widely spaced ends of conductors 10, 11 are supported above ground by ropes 29 attached to supporting poles (not shown).

An embodiment of the form of the invention shown in Figure 1, using the dimensions shown in the figure, and operated at a frequency of 3.53 meters had a coefficient of reflection of the order of 4.5 percent and less than 10 percent over a 10 very wide range. This, it will be seen, is markedly better than the coefficient of reflection of the order of 50 to 60 percent usually obtained with an unterminated V antenna utilizing single wires in each conductor.

In Figure 2 is shown a modification of one of the conductors of the antenna of Figure 1. Here, the conductor 10 has, as in the case of Figure 1, all of the wires terminating at a point where it is connected to one of the conductors of transmission line TL. For a portion of the length of the conductor the wires are arranged in a conical configuration and maintained in this arrangement by spacing rings 32. Then, for the remainder of the length of the conductor the wires are arranged in a flattened fan-like configuration and attached in vertical alignment through insulators 33 along supporting post 34. The conical portion of the conductor may be of the order of 48 feet or 14.6 meters or slightly less than half of the overall length of the order of 120 feet or 36.5 meters. No reflection whatever may be observed when the wavelength of the energy applied by the antenna by transmission line TL is varied over a range of from 6.1 meters to 6.5 meters. In this frequency range the length of the conductor 10 approximated 6 wavelengths. For higher frequencies where the length of conductor 10 approximates 10 wavelengths the reflection is observed to increase somewhat. It is believed that this may be due to the effect of the insulators, etc., at the junction of the cone and fan portions of the conductor.

The proportions of the conical conductors 10, 11 are so chosen as to give the same characteristic impedance as the wires of the transmission line TL feeding the antenna. The characteristic of an impedance V antenna with conical conductors where α is the half angle of the V and ϕ , the angle of revolution of the cone may be determined from the relation

$$Z = 120 \log_{\phi} \frac{2\alpha}{\phi}$$

A further modification of the present invention is shown in Figure 3 wherein the conductors 10' and 11' are single wires terminated at the end remote from their point of connection to transmission line TL by conical structures 30 and 31. The cones may be constructed of relatively thin sheet copper. The overall length of each of the conductors 10' and 11' may be of the order of 10 wavelengths with the conical end portions 30 and 31 having lengths of the order of .36 wavelength. Tests indicate that without the conical end portions the energy reflected back along the antenna wires near the middle thereof was of the order of 58 percent while addition of the cones 30 and 31 reduces the reflection to 27½ percent. Substituting cones constructed of 16 wires each 12 feet or 3.65 meters in length and having a base diameter of the order of 18 inches or a little less than a half meter for the solid sheet metal cones causes a reduction of the coefficient of reflection along the antenna wires to a figure of the order

of 19.7 percent. An increase of the wavelength to 3.73 meters is accompanied by a corresponding decrease in the reflection to 18.6 percent. Utilizing the same antenna at nearly double the wavelength making the length of the antenna of the order of 5 wavelengths and the length of the conical terminating portions about a half wavelength increases the reflection on the antenna wires to 38 percent. Increasing the diameter of the base circle of the cones from 18 inches to 28 inches or .85 meter reduces the reflection along the antenna to 11.7 percent at a wavelength of 3.65 meters and to 17.3 percent at 3.5 meters. Coefficients of reflection under 16 percent may be obtained for a very wide range of operating wavelengths.

Curve 40 in Figure 4 illustrates the distribution of current along the length of a single conductor of an unterminated single wire V antenna such as that described above with reference to Figure 3 but with the terminating cones omitted. It will be noted that current loops of substantial amplitude are uniformly spaced along the entire length of the conductor, the maxima following line 41 and the minimum line 42. The ratio of the ordinates of lines 41 and 42 is of the order of 3.75, resulting in a coefficient of reflection of the order of 58 percent. Adding terminating cones such as shown in Figure 3 to the single wire V antenna results in a reduction in the difference of the ordinate values of lines 41' and 42' following the current maxima and minima of current curve 40' (Figure 5). There the ratio of maximum to minimum current values is only 1.29 resulting in a coefficient of reflection of only 12.7 percent.

The curves of Figure 6 illustrate the manner in which the percentage of reflection varies with a variation of the wavelength applied to the antenna of Figure 3 utilizing wire cone terminations having the base circle diameters of 28 inches.

It will be noted that the maximum reflection in the wavelength range from 3.5 to 3.77 meters, as indicated by curve 50, does not exceed 17½ percent with a minimum coefficient of reflection of the order of 12 percent at a wavelength of 3.66 meters. An increase in the wavelength causes an increase of reflection up to a maximum of 46 percent at 6.2 meters and a minimum of 33 percent at 6.45 meters, as indicated by curve 51.

While I have illustrated particular embodiments of the present invention it should be clearly understood that the invention is not limited thereto since many modifications may be made in the several elements employed and in their arrangement and it is, therefore, contemplated by the appended claims to cover any such modifications as fall within the spirit and scope of the invention.

I claim:

1. A traveling wave antenna, including a conductor having a length greater than at least several multiples of the operating wavelength, said conductor being coupled to wave transducer means at one end and tapering from a large transverse dimension at the free end toward said one end, said taper being so chosen that energy travels along said conductor solely from one end to said free end.

2. A traveling wave antenna, including a conductor having a length greater than at least several multiples of the operating wavelength, said conductor being coupled to wave transducer means at one end and tapering from a large transverse dimension at the free end toward said

one end, said taper being so chosen that energy travels along said conductor solely from one end toward said free end, the tapering portion of said conductor having a length of the order of .36 to one wavelength.

3. A traveling wave antenna, including a conductor having a length greater than at least several multiples of the operating wavelength, said conductor being coupled to wave transducer means at one end and tapering from a large transverse dimension at the free end toward said one end, said taper being so chosen that energy travels along said conductor solely from one end to said free end, said conductor including a plurality of wires arranged along the length of the surface of the cone.

4. A traveling wave antenna, including a conductor having a length greater than at least several multiples of the operating wavelength, said conductor being coupled to wave transducer means at one end and tapering from a large transverse dimension at the free end toward said one end, said taper being so chosen that energy travels along said conductor solely from one end to said free end, said conductor including a plurality of wires arranged along the length of the surface of a cone having an apex angle of from 27 to 30 degrees.

5. A traveling wave antenna, including a conductor having a length greater than at least several multiples of the operating wavelength, said conductor being coupled to wave transducer means at one end and tapering from a large transverse dimension at the free end toward said one end, said taper being so chosen that energy travels along said conductor solely from one end to said free end, said conductor including a plurality of wires arranged along the length of the surface of a cone for a portion of the length of said conductor and arranged in a flat fan formation at said free end.

6. A traveling wave antenna, including a conductor having a length greater than at least several multiples of the operating wavelength, said conductor being coupled to wave transducer means at one end and tapering from a large transverse dimension at the free end toward said one end, said taper being so chosen that energy travels along said conductor solely from one end to said free end, said conductor including a plurality of wires arranged along the length of the surface of a cone for substantially half of the length of said conductor and arranged in a flat fan formation for the remainder of the length of said conductor.

7. A traveling wave antenna, including a pair of conductors arranged in a V formation, said conductors being coupled to wave transducer means at the apex of said V, each of said conductors tapering from a large transverse dimension at their free ends toward the apex of said V, said taper being so chosen that energy travels along said conductors solely from the apex of said V to said free ends.

8. A traveling wave antenna, including a pair of conductors arranged in a V formation, said conductors being coupled to wave transducer means at the apex of said V, each of said conductors tapering from a large transverse dimension at their free ends toward the apex of said V, the taper of said conductors being so related to the angle between said conductors that no reflection of energy takes place from said free ends of said conductors.

9. A traveling wave antenna, including a pair

of conductors arranged in a V formation, said conductors being coupled to wave transducer means at the apex of said V, each of said conductors tapering from a large transverse dimension at their free ends toward the apex of said V, the taper of said conductors being so related to the angle between said conductors that no reflection of energy takes place from said free ends of said conductors, each of said conductors including a plurality of wires arranged along the length of the surface of a cone.

10. A traveling wave antenna, including a pair of conductors arranged in a V formation, said conductors being coupled to wave transducer means at the apex of said V, each of said conductors tapering from a large transverse dimension at their free ends toward the apex of said V, the taper of said conductors being so related to the angle between said conductors that no reflection of energy takes place from said free ends of said conductors, each of said conductors including a plurality of wires arranged along the length of the surface of the cone for substantially half the length of each of said conductors adjacent the face of said V and said wires being arranged in a flat fan formation at said free ends.

11. A traveling wave antenna, including a pair of conductors arranged in a V formation, said conductors being coupled to wave transducer means at the apex of said V, each of said conductors tapering from a large transverse dimension at their free ends toward the apex of said V, the taper of said conductors being so related to the angle between said conductors that no reflection of energy takes place from said free ends of said conductors, each of said conductors including a plurality of wires arranged along the length of the surface of the cone for substantially half the length of each of said conductors adjacent the face of said V and said wires being arranged in a flat fan formation at said free ends, the plane in which the free ends of said conductors of said fan formation lie, being vertical.

12. A traveling wave antenna, including a conductor having a length greater than at least several multiples of the operating wavelength, said conductor being coupled to a transmission line at one end and tapering from a large transverse dimension at the other end toward said one end, said taper being so chosen that energy travels along said conductor solely from one end to said other end.

13. A traveling wave antenna, including a conductor having a length greater than at least several multiples of the operating wavelength, said conductor being coupled to a transmission line at one end and tapering from a large transverse dimension at the other end toward said one end, said taper being so chosen that energy travels along said conductor solely from one end to said other end, said conductor including a plurality of wires arranged along the length of the surface of the cone.

14. A traveling wave antenna, including a pair of conductors arranged in a V formation, said conductors being coupled to a transmission line at the apex of said V, each of said conductors tapering from a large transverse dimension at their other ends toward the apex of said V, said taper being so chosen that energy travels along said conductors solely from the apex of said V to said other ends.

15. A traveling wave antenna, including a pair of conductors arranged in a V formation, said

conductors being coupled to a transmission line at the apex of said V, each of said conductors tapering from a large transverse dimension at their other ends toward the apex of said V, the taper of said conductors being so related to the angle between said conductors that no reflection of energy takes place from said other ends of said conductors.

16. A traveling wave antenna, including a pair of conductors arranged in a V formation, said conductors being coupled to a transmission line at the apex of said V, each of said conductors tapering from a large transverse dimension at

their other ends toward the apex of said V, the taper of said conductors being so related to the angle between said conductors that no reflection of energy takes place from said other ends of said conductors, each of said conductors including a plurality of wires arranged along the length of the surface of the cone for substantially half the length of each of said conductors adjacent the face of said V and said wires being arranged in a flat fan formation at said other ends.

PHILIP S. CARTER.
